(57) **CLAIM**

The ornamental design for a bottle top grinder, as shown and described.

DESCRIPTION

FIG. 1 is a top isometric view of the present design a bottle top grinder.

FIG. 2 is a bottom isometric view of the present design.

FIG. 3, with reference to FIG. 7 wherein north is the top of the page, is a south side plan view of the present design.

FIG. 4, with reference to FIG. 7, is a north side plan view of the present design.

FIG. 5 with reference to FIG. 7, is a west side plan view of the present design.

FIG. 6 with reference to FIG. 7, is a east side plan view of the present design.

FIG. 7 is a top plan view of the present design.

FIG. 8 is a bottom plan view of the present design.

FIG. 9 is a top isometric view of the present design shown deployed in a bottle top at a low level.

FIG. 10 is a top isometric view of the present design shown deployed in a bottle top at a higher level.

FIG. 11 cross sectional view taken along lines 11-11 of FIG. 9 showing the present design deployed in a bottle top at a low level; and,

FIG. 12 cross sectional view taken along lines 12-12 of FIG. 10 showing the present design deployed in a bottle top at a higher level.

The broken lines shown in the Figures which illustrate portions of the bottle top grinder form no part of the claimed design.

The Broken lines shown in FIGS. 9, 10, 11 and 12 showing a bottle illustrate environmental subject matter only and form no part of the claimed design.

1 Claim, 8 Drawing Sheets
